Primary Examiner — Karen S Acker*Assistant Examiner* — Omeed Agilee(74) *Attorney, Agent, or Firm* — Neal, Gerber & Eisenberg LLP; Thomas E. Williams(57) **CLAIM**

The ornamental design for a bottle, as shown and described.

DESCRIPTION

FIG. 1 is a front, right, and top perspective view of a bottle, showing our new design;

FIG. 2 is a front, right, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines are included for illustrating portions of the bottle that form no part of the claimed design.

1 Claim, 6 Drawing Sheets(56)
